UNITED STATES PATENT OFFICE.

EMORY B. CLIFTON, OF WITHEE, WISCONSIN.

CONVERTIBLE COT AND STRETCHER.

SPECIFICATION forming part of Letters Patent No. 694,353, dated March 4, 1902.

Application filed September 30, 1901. Serial No. 77,125. (No model.)

To all whom it may concern:

Be it known that I, EMORY B. CLIFTON, a citizen of the United States, and a resident of Withee, in the county of Clark and State 5 of Wisconsin, have invented certain new and useful Improvements in Convertible Cots and Stretchers; and I do hereby declare that the following is a full, clear, and exact description thereof.

10 My invention relates to a bed adapted to be quickly converted into either a cot or stretcher, as desired, and to be capable of being rolled up when not in use, so as to occupy very small space in either storage or transportation; and it consists in certain peculiarities of construction and combination of parts, as will be fully set forth hereinafter in connection with the accompanying drawings and subsequently claimed.

20 In the said drawings, Figure 1 is a view in side elevation, partly in vertical longitudinal section, of my said device arranged for use as a cot. Fig. 2 is a view of the same in end elevation. Fig. 3 is an under side plan view 25 of my device arranged as a stretcher. Fig. 4 is a longitudinal sectional view of the same, taken on the line A A in Fig. 3. Fig. 5 is a plan view of my device with the parts arranged for storage or transportation and 30 shown partially rolled up.

Referring to the drawings, *ab* represent the side bars of my device, the side bar *a* being of increased thickness at one end on its under side, forming the downward extension *c*, with a 35 transverse groove *d* therein, and a pivoted button *e*, adapted to be swung across said groove when desired, and the side bar *b* having a similar increased thickness or downward depression *f* at the opposite end, with a like transverse groove *g* therein and a similar pivoted button *h*. The side bar *a* has a 40 longitudinally-extending handle *i* at each end, and the side bar *b* is provided with a like pair of handles *j*.

45 Attached to one end of the side bar *a* by pivot *k* is the frame-brace *m*, having recess *n* in its free end, which end engages with the groove *g* in side bar *b*, and attached to the opposite end of the side bar *b* by pivot *o* is a like frame-brace *p*, with like recess *q* at its 50 free end, which end engages with the described groove *d* in side bar *a*. A covering *r*

extends across from side bar *a* to side bar *b*, being secured to the outer edges of said side bars, as by the nails or screws *s s s*, and 55 this covering forms the bed proper, whether the device is used as a cot or stretcher. When used as a cot, the legs and leg-braces, about to be described, are brought into service, there being four legs (marked, respectively, 60 *t, u, v* and *w*) and two leg-braces (marked *x* and *y*); but when the device is to be used as a stretcher these legs and leg-braces are folded up in the manner to be presently described (and shown in Figs. 3 and 4) and held by the 65 hooks *z z*, which depend from the side bars *a b*.

The leg *t* is pivotally secured to one end of the side bar *a* by the pivot-bolt *l* just inside of the line of the frame-brace *p*, the said leg *t* having a transverse groove *2* across it at a 70 point near its free end and carrying a pivoted button *3* adjacent thereto. The leg *u* is pivotally secured to the side bar *b* at the opposite end of the device by the pivot-bolt *4* just inside the line of the frame-brace *m*, the 75 said leg *u* also having a transverse groove (marked *5*) and a pivoted button (marked *6*) adjacent to its free end. The leg *v* is pivotally secured by the pivot-bolt *7* to side bar *b* just inside the line of the frame-brace *p*, and 80 the leg *w* is pivotally secured by the pivot-bolt *8* to side bar *a* just inside the line of the frame-brace *m*. The leg-brace *x* is secured by pivot-bolt *9* to the free end of leg *v*, and the free end of said brace *x* has a recess 85 *10* therein, said recessed end engaging with the groove *2* in leg *t*, while the leg-brace *y* is secured by pivot-bolt *11* to the free end of leg *w*, and the free end of this brace *y* has a recess *12* therein, this recessed end engaging 90 with the groove *5* in leg *u*.

The operation of my invention will be readily understood from the foregoing description of its construction, taken in connection with the accompanying drawings. In Figs. 1 and 95 2 the device is shown arranged as a cot and the same can be instantly converted into a stretcher by folding the legs inward, leaving them still connected by the leg-braces and engaging the leg *t* with one of the hooks *z* 100 and the leg *u* with the other hook *z*, which will prevent the legs and their attached parts from falling down. When the device is not in use and it is desired to store or transport

same with the greatest economy of space, the device is inverted, as shown in Fig. 3, the buttons *e* and *h* are swung back, the recessed ends of the frame-braces *m p* lifted out of the grooves *d g* in the side bars, and said braces swung around on their pivots *k o*, so as to rest on the side bars *a b*. The buttons *3 6* on the legs *t u* are swung back and the recessed ends of the leg-braces *x y* lifted out of the leg-grooves *2 5* and said leg-braces swung around on their pivot-bolts *9 11* parallel to and against the side-bars *a b*, the leg-brace *x* then overlapping the leg *u* and the leg-brace *y* similarly overlapping the leg *t*, and then the device rolled together, as indicated in Fig. 5, so that the described movable legs and braces are substantially wrapped up by the covering *r*, in which condition the device will occupy but little space and yet be ready for instantaneous adjustment either as a cot or stretcher, as desired, thus making a most convenient article for hospitals and camps as well as for hotel or other use.

Having thus described my invention, what I claim as new, and desire to secure by Letters Patent, is—

1. A convertible cot and stretcher, comprising a pair of side bars, united by a flexible covering forming the bed proper, said side bars being transversely grooved, on their under surfaces, one at one end, and the other at its opposite end, in combination with pivoted frame-braces secured to the ungrooved ends of the opposed side bars and recessed at their free ends for engagement with the grooves in the side bars; pivoted buttons on the side bars for retaining the frame-braces in their

engaged positions; folding legs pivotally secured to said side bars; and depending pivoted hooks for securing said legs in folded position. 40

2. A convertible cot and stretcher, comprising a pair of side bars, united by a flexible covering, forming the bed proper, said side bars being transversely grooved, on their under surfaces, one at one end, and the other at its opposite end, and provided with pivoted retaining-buttons adjacent to said grooves, in combination with pivoted frame-braces, secured to the opposite ends of the said side bars, and recessed at their free ends for engagement with said grooves in the side bars; two pairs of folding legs pivotally secured to said side bars, each pair being pivoted just inside the line of the adjacent frame-brace, 45 and one leg of each pair being transversely grooved across the under surface of its free end, and provided with a pivoted retaining-button adjacent to said groove; a pair of pivoted leg-braces, each brace being secured to 50 the free end of the non-grooved leg, and itself recessed at its free end for engagement with the grooved leg, in each pair of folding legs; and means for securing said legs in folded position, parallel to and against said side bars. 55

In testimony that I claim the foregoing I have hereunto set my hand at Withee, in the county of Clark and State of Wisconsin, in the presence of two witnesses.

EMORY B. CLIFTON.
